UNITED STATES PATENT OFFICE.

JOSEPH TORCHIA, OF CINCINNATI, OHIO.

BLOOMERS.

Application filed August 12, 1922. Serial No. 581,337.

To all whom it may concern:

Be it known that I, JOSEPH TORCHIA, a citizen of the United States, residing at Cincinnati, in the county of Hamilton and State of Ohio, have invented certain new and useful Improvements in Bloomers, of which the following is a specification.

My invention relates to improvements in bloomers for ladies and misses.

10 The object of my invention is to provide simple, efficient, convenient and economical means for opening and closing the back and crotch of a garment for the convenience of the wearer for the purpose of answering the calls of nature and for convenient access 15 in attaching or removing a sanitary menstrual napkin or for other purposes.

My invention consists in providing a central vertical opening, such as a slit or slot 20 from the front of the crotch to near the back waist line of the garment and with lateral or extended openings at each side of the crotch with a covering flap or panel attached at its upper end to near the rear 25 top of the garment and adapted to extend over said opening between the legs and having means for attaching its free end to the front of the garment.

My invention also consists in the peculiar 30 construction, combination and arrangement of parts as herein set forth and claimed.

In the drawings:

Fig. 1 is a front view of a bloomer embodying my invention;

35 Fig. 2 is a rear view thereof;

Fig. 3 is a rear view showing the free end of the closing flap detached and drawn to one side to show the sides of the opening held in close proximity by the fastening tab;

40 Fig. 4 is a similar view showing the fastening tab detached and the sides of the opening drawn apart to more clearly illustrate the interior construction;

Fig. 5 is a fragmental rear view of the 45 garment showing the construction of the crotch and other parts;

Fig. 6 is a vertical section taken on the line 6—6 of Fig. 1;

Fig. 7 is an inside view of the closing 50 flap showing a sanitary menstrual napkin secured thereon;

Fig. 8 is a front view of the bloomer showing the closing flap detached; and

55 Fig. 9 is a rear elevation showing the covering flap in dotted lines.

In the embodiment of my invention as il-

lustrated and which shows a preferred construction the bloomer 1 is preferably provided with a waist band 2 having a longitudinal passage-way 3 in which an elastic band 4 is inserted to form means for holding and supporting the garment in proper position upon the wearer. The waist band is preferably formed sufficiently large to permit the goods to form gathers 5 when the elastic band is contracted or partly contracted for the purpose of providing a wide range of adjustment to different sizes of persons. The rear sides 6 and 7 of the garment are separated by a vertical opening 8 60 extending from the waist band 2 to the front of the crotch 9 and is provided with branch slots 10 and 11 extending downwardly to the closing seams 12 and 13, respectively, of the legs 14 and 15, respectively. This peculiar construction of the bloomer at the crotch provides for a wide and free opening of the garment in the rear and at the lower front extremity of the garment to furnish a large opening for the user when seated without any binding of the garment across the legs or hips and without danger of tearing or ripping the garment under said conditions. It also provides for convenient, free and unobstructed 70 access of the hands to the person.

Reinforcing patches 16 and 17 are preferably inserted and assist in forming a strong base on which to mount the fastener eyelets 18 and 19. The front of the crotch 90 9 extends upwardly providing a short front slot 20 adjacent branch slots 10 and 11 for the purpose of assisting in spreading or extending the opening and of gaining free access to the person from the front.

A covering flap 21 is attached to the rear sides 6 and 7 and preferably extends over and around waist band 2 to which it is stitched. It is also preferably stitched to the rear sides 6 and 7 from the waist band as shown by stitches 22 to hold said parts in close proximity to the edge at that point, as clearly shown in Fig. 9. Said covering flap is gradually widened centrally and tapers toward its free end. It is sufficiently wide throughout its length to completely cover opening 8 and slots 10, 11 and 20. Snaps 23 and 24 are placed upon the inner side of the free end of flap 21 and are adapted to engage eyelets 18 and 19, respectively, to detachably hold said flap in closed position, but other suitable fas-

tenting means, such as hooks and eyes may be used.

If desired and when necessary a sanitary menstrual napkin 25 may be suitably attached by safety pins 26, or otherwise, to the inner face of closing flap 21 at the proper position thereon to perform its usual functions.

Tab 27 preferably detachably holds back 10 rear sides 6 and 7 in close relation to each other as shown in Figs. 3 and 9.

The closing flap or panel may be made of rubberized cloth or other equivalent material for the purpose of preventing staining the 15 outer garments due to menstrual flow and the like in which case the panel may be readily washed without washing the garment.

Heretofore bloomers have been made 20 without any convenient and accessible rear and bottom opening and when the user desired to gain access to the nether or private organs or to perform the calls of nature it was necessary to shift the garment down 25 from the waist upon the legs below said nether organs, thus making it necessary to lift up the outer garments inconveniently high for such purpose and entailing much inconvenience in the adjustment of the garments to open or closed position.

Bloomers have also been made with a drop seat or flap secured at its upper end by buttons at each side at the waist line but such arrangement is very inconvenient and 35 also requires lifting the outer garments inconveniently high to gain access and the buttons must be attached or detached at the back or side at great inconvenience to the user. Furthermore, when the user is seated 40 with such latter type of bloomer the adjacent edge of the flap and body of the bloomer will spread and gap thereby exposing the person to the weather and if no other garment is being worn would expose the 45 person at that time.

With such type of bloomer also it is impossible to provide an adequate opening for convenience and ease of the user while seated upon a toilet as the sides of the garment will bind upon the hips and the drop flap will be in the way of the user. My bloomer is preferably provided with a completely closed flexible waist band the same as in ordinary bloomers and thereby insures 50 holding the bloomer in position on the wearer, whereas if either button of the drop flap type of bloomer becomes loose or unbuttoned the bloomer is free to drop down upon the floor with possible embarrassment 55 to the wearer.

An important advantage of my bloomer is that it enables the user free and convenient

access for the purpose of applying or removing a sanitary menstrual napkin which may be conveniently attached at each end to the 65 inside closing flap of the bloomer so that it may be conveniently moved out of the way with the flap without detaching it therefrom at such times as required or desired.

My invention is particularly convenient 70 for use in opening and closing the opening 8 since the free end of the closing flap 21 is detachably connected to the lower front part of the garment at a point of convenient access to the hands of the user without the 75 necessity of lifting the outer garments or reaching up to the top and rear part of the bloomer to obtain the desired result of opening it, or of shifting it down over the person from the rear which is frequently required. 80

While I have illustrated my invention as applied to a bloomer having a closed flexible retaining waist band it will be understood that it may also be applied to modified constructions such as a non-flexible separable 85 band having its ends detachably connected by buttons or otherwise, and while I have shown a particular construction and arrangement of my invention it will also be understood that it is capable of modification without departure from its scope or spirit as defined in the claims.

What I claim as new and desire to secure by Letters Patent is:

1. In a bloomer having a rear central 95 opening extending from substantially at the waist-band to the front of the crotch, a closing flap attached at the rear of the bloomer substantially at the waistband of the bloomer and adapted to extend over said opening 100 and crotch to close the opening, and to be detachably connected to the front of the bloomer.

2. In a bloomer having a rear opening extending downwardly through the crotch and having a fastening means on one side thereof, a tab secured to one side of said opening and adapted to be attached across said opening to said first named fastening means, and a flap adapted to cover said opening and permanently attached to the bloomer at the upper rear end of said opening and detachably connected to the bloomer at its front. 105

3. In a bloomer having a completely 115 closed waist-band and having a rear central opening extending substantially from said waist-band to the front of the crotch, a closing flap attached substantially at the waistband of the bloomer and adapted to extend over said opening and crotch to close the opening, and means to detachably connect said closing flap to the front of the bloomer. 120

JOSEPH TORCHIA.
